UNITED STATES PATENT OFFICE

114,371

DESIGN FOR A CRIB

Edmond J. Spence, Batavia, N. Y., assignor to
The Lehman Company of America, Inc., Can-nelton, Ind., a corporation of Indiana

Application January 13, 1939, Serial No. 82,327

Term of patent 14 years

To all whom it may concern:

Be it known that I, Edmond J. Spence, a citizen of the United States, residing at Batavia, in the county of Genesee and State of New York, have invented a new, original, and ornamental Design for a Crib, of which the following is a specification, reference being had to the accompanying drawing, forming a part thereof.

In the drawing:

The single figure is a perspective view of the crib showing my design. The left-hand end of the crib which is not fully shown in the drawing is substantially similar to the right-hand end which is shown.

I claim:

The ornamental design for a crib, substantially as shown and described.

EDMOND J. SPENCE.
